UNITED STATES PATENT OFFICE.

ANTON BECKER, OF COLUMBUS, OHIO, ASSIGNOR TO THE RALSTON STEEL CAR COMPANY,
OF COLUMBUS, OHIO.

UNDERFRAME FOR CARS.

No. 899,649.

Specification of Letters Patent.

Patented Sept. 29, 1908.

Application filed January 14, 1908. Serial No. 410,792.

To all whom it may concern:

Be it known that I, ANTON BECKER, of Columbus, in the county of Franklin and State of Ohio, have invented certain new and useful Improvements in Underframes for Cars; and I do hereby declare the following to be a full, clear, and exact description of the invention, such as will enable others skilled in the art to which it appertains to make and use the same.

My invention relates to improvements in underframes for cars and more particularly an underframe adaptable for use in the construction of such four-wheeled vehicles as 15 cabooses,—the object of the invention being to so construct the underframe that it will be supported upon the pedestals over the car axles, and so that side-sills of ordinary "depth" can be employed and made to 20 operate with the smaller furring strip to support the car flooring.

With this object in view the invention consists in certain novel features of construction and combinations of parts as herein- 25 after set forth and pointed out in the claims.

In the accompanying drawings, Figure 1 is a transverse sectional view illustrating a car underframe embodying my improvements. Fig. 2 is a partial longitudinal section showing the relation of an end-sill and platform to the center girder, and Fig. 3 is a 30 sectional view on the line $x-x$ of Fig. 2.

1 represents a center girder comprising two channeled members and is supported 35 through the medium of cross-beams 2 upon angle beams, preferably having Z-shape in cross-section, such Z-beams being located adjacent to the sides of the frame and supported upon the pedestals 3 over the jour- 40 nal-boxes of the car.

Each cross-beam 2 comprises two members, each consisting of a channel-iron secured at its inner end to one member of the center girder by means of an angle-plate 4, or if desired the inner end of each cross-beam member may be provided with a flange to lie 45 against a center beam member and be riveted thereto. The outer end of each cross-beam member projects laterally beyond one 50 of the Z-beams, rests thereupon and is secured thereto by means of bolts or rivets.

A top compression plate or strap 5 extends across the center sill and is secured to the upper flanged edges of the respective members of the cross-beams. A lower com-

pression plate 6 passes through slots in the center sill members and is secured at its ends to the lower flanges of the cross-beam members,—these compression plates assisting in insuring the rigidity of the connection of the 60 cross-beam members with the center girder.

In the ordinary construction of cars, in which wooden side sills are employed, such sills are made of greater depth than the furring strips but their upper faces are made to 65 align with the upper faces of the furring strips for the accommodation of the car flooring. In the present instance, furring strips 7 are located upon the cross-beams and for the accommodation of the thicker or 70 deeper side sills 8, I provide brackets 9. Each of these brackets comprises two angle-irons secured at respective sides of each cross-beam member at the end of the latter and in proximity to the lower flanged edge thereof. 75 These brackets project outwardly from the end of the cross-beam member and constitute a seat for the side-sill as clearly shown in Fig. 1. The end sills 10 (which also assist in supporting the floor) are made of greater 80 depth or thickness than the furring strips, and for their accommodation the respective center girder members are notched, as at 11, and the flanged upper portions are bent outwardly and downwardly to form depressed 85 seats 12 upon which the end sill rests. Each end sill is also braced by means of an angle-iron 13 secured to the side thereof and the center girder. The end sills are also supported near their ends by brackets 15 secured thereto and to the Z-bars 3. The center girder projects beyond the end-sills and supports the car platform 14.

The side Z-beams may be secured to the car pedestals in any suitable manner and various changes might be made in other details of construction without departing from the spirit of my invention.

By the "angle-beams" as used in the claims, is meant beams having webs, and flanges disposed substantially at right angles to the webs.

Having fully described my invention what I claim as new and desire to secure by Letters-Patent, is,—

1. A car underframe comprising angle-beams adapted to be supported upon the car pedestals, a center girder, cross-beams supporting the center girder upon the side angle-beams, and brackets projecting from the ends 105 110

of the cross-beams below the upper face of the latter for supporting side-beams.

2. A car underframe comprising side angle-beams adapted to be supported upon the car pedestals, a center girder, cross-beams supporting the center girder upon the side angle-beams, and depressed seats projecting from the ends of the cross-beams for the reception of side-sills.

10 3. A car underframe comprising angle-beams adapted to be supported upon the car pedestals, a center girder between said angle-beams, cross-beam members secured at their inner ends to the center girder, said cross-beam members resting upon and projecting laterally beyond the angle-beams, and angle-irons secured to the outer ends of the cross-beam members below the upper faces of the latter, said angle-irons projecting outwardly 20 beyond the ends of the cross-beam members and constituting seats for the side-sills of the car.

4. The combination with a center sill adapted at its ends to support car platforms 25 and provided with notches and depressed seats adjacent to said platforms, of end sills resting upon said depressed seats and passing through said notches, cross-beams secured to the center girder, depressed seats at 30 the ends of said cross-beams, and side-sills

resting upon said last mentioned depressed seats.

5. The combination with a center girder provided near its ends with notches and integral laterally projecting seats at the bases 35 of said notches, of end sills resting upon said seats, cross-beams secured to the center girder, depressed seats projecting outwardly from the ends of the cross-beams, side-sills mounted upon said depressed seats, and 40 means for supporting the transverse beams upon the car pedestals.

6. The combination with a center girder provided near its ends with recesses and depressed seats at the bases of said recesses, of 45 end-sills passing through said recesses and resting upon said depressed seats, angle-irons secured to said end sills and to the center girder, cross-beam members secured to the center girder and adapted to support the 50 side-sills of the car, and means for supporting said cross-beams upon the car pedestals.

In testimony whereof, I have signed this specification in the presence of two subscribing witnesses.

ANTON BECKER.
